ORVIS W. VALLIER, OF WATERTOWN, NEW YORK, ASSIGNOR TO J. B. WISE INCORPORATED, OF WATERTOWN, NEW YORK, A CORPORATION OF NEW YORK.

WASTE-OPERATING MECHANISM.

Application filed January 6, 1923. Serial No. 611,046.

To all whom it may concern:

Be it known that I, ORVIS W. VALLIER, a citizen of the United States, residing at Watertown, in the county of Jefferson and 5 State of New York, have invented certain new and useful Improvements in Waste-Operating Mechanism, of which the following is a specification.

This invention relates to improvements 10 in waste operating mechanisms, designed particularly for use in connection with "built-in" bath fixtures, with which are associated the well-known standing waste and over-flow including the usual gravitational 15 plunger type of waste valve.

The object of the invention is to provide novel, simple and handly mechanism for operating the waste plunger, which consists in part of an eccentric rockable member, a handle, and an adjustable grapple which is interposed between the eccentric member and the waste plunger, the said eccentric member being freely rockable in opposite directions for unseating and seating 20 the waste valve. And a further object is to provide novel means for adjusting certain important parts of the operating mechanism.

I attain these objects by the means set 30 forth in the detailed description which follows, and as illustrated by the accompanying drawings, in which—

Figure 1 is a broken elevational view of a bath-room, looking towards the head of the 35 bath-tub. Fig. 2 is a side view of the same, the wall being in section for exposing the hidden fittings. Fig. 3 is a top plan view, taken in the direction of the arrow in Fig. 2. Fig. 4 is a rear elevation of the fittings, taken in the direction of the arrow in Fig. 40 5. Fig. 5 is an enlarged view, taken substantially on line 5—5 of Fig. 6. Fig. 6 is a horizontal section, taken on line 6—6 of Fig. 2. Fig. 7 is a view of the adjusting 45 sleeve and nut. Fig. 8 is respectively a face and an edge view of the grapple. And Fig. 9 is respectively a side and an edge view of the eccentric member.

In the drawings, 2 represents one of the 50 hollow walls of a bath-room, in which the major portion of the bath fittings are disposed, and 2^a is the floor. 3 represents a bath-tub, the head-end of which is shown

in contact with the wall 2. The water enters the tub through a spout 3^a, which 55 may be disposed at the head-end 3', and the waste and over-flow is effected through a bottom opening 3^b, from which opening the water is carried to a waste-valve fitting 4, that is located in the wall 2 near the 60 floor level, by a pipe 5. The valve fitting 4 connects directly to a soil-pipe 6, and to an alining stand-pipe 7, of the waste fitting, the latter rising from the valve casing 4, and being normally in unrestricted communication with the pipe 5 and the tub 3, so that the filling of the tub 3 with water, correspondingly fills the stand-pipe 7. The 65 spout 3^a and the drain outlet 3^b are both normally open. The level in the bath-tub, 70 as well as the passage of the waste water into the soil-pipe 6, is controlled by a gravitational plunger 8, which loosely telescopes the stand-pipe 7, the said plunger being 75 hollow throughout and of considerably smaller diameter than the pipe 7. The bottom end of the plunger 8 comprises the waste valve 8', and when the plunger is in the lowermost position, the valve 8' is received in a seat 4' of the part 4, which is 80 arranged above and concentric to the soil-pipe 6. The plunger 8 is held in its seat arranged above and concentric to the soil-pipe 6. The plunger 8 is held in its seat entirely by gravity. The plunger 8 extends upwardly through the pipe 7, and its projecting top-end 8^a is externally threaded, for 85 adjustably receiving a hollow internally threaded cap 9, which may be locked in place after each adjustment by a circular nut 9'. At a suitable distance below the top-end of the stand-pipe 7, the plunger 8 90 is provided with a series of over-flow openings 8^b, by which the depth of the water in the tub and stand-pipe may be regulated. The dotted lines α in Figs. 2 and 4 indicate the normal level of the wa- 95 ter in the tub 3. All excess water entering through the spout 3^a, flows through the plunger openings 8^b, and thence gravitates directly into the soil-pipe 6. The cold and hot water may be supplied to the fitting 100 by separate pipes 10 and 10', which discharge the water into any kind of cocks 12, which may be controlled by similar valve-stems 12', and handles 12^a, the said handles and portions of the stems being disposed outside of the wall 2, preferably convenient

to the head 3' of the tub, as shown in Figs. 1, 2, 3 and 6. From the cocks 12 the hot and cold water passes into a mixing pipe 13, the latter being fitted with a T 13', from which a common pipe 13^a conducts the combined cold and hot water to the spout 3^a. The supply of the water to the tub 3 is controlled entirely by the cocks 12.

The closed top-end of the cap 9 is slotted 10 for providing an expanded loop 9^a, by which the cap and the plunger 8 may be lifted away from the seat 4'. The lifting of the plunger 8, for discharging the waste water into the soil-pipe 6, is effected by a grapple 14 or lifter 14, which preferably comprises a single length of heavy wire, which is folded upon itself to provide a relatively large rectangular loop 14' and similar legs 14^a, the free ends of the legs being bent at right angles to provide feet 14^b, which are inserted loosely through the loop 9^a of the cap 9, as best seen in Figs. 2, 3, 4, 5 and 6. The grapple 14 is supported and operated by a member 15, the latter comprising two similar 20 and registering discs 15^a—15^b, which are spaced apart by two pins 16, and a sleeve 16'. The loop 14' of the grapple is disposed between the two discs and loosely surrounds and rides upon either the pins 16, or the 30 sleeve 16', as shown by the dotted and full lines in Figs. 4 and 5. The discs 15^a—15^b are mounted eccentrically upon and are operable in opposite directions as one part, by a shaft 17, which passes through both of the 35 discs and its inner end is preferably riveted in the disc 15^a. The shaft 17 extends from the disc 15^b through a plate 18, which may be secured to the inner face of the wall 2, by screws 18'. From the plate 18 the shaft 40 17 passes through an opening in the wall 2, thence through a hollow conical part 19, which supports the outer end of the shaft to which a handle 17' is secured. The pins 16 form a relatively broad base of a triangle, the apex of which is the shaft 17. When the member 15 is in the position shown 45 by full lines in Figs. 2 and 4, the top arm 14^c of the loop 14' of the grapple rides on the sleeve 16' (or apex), and while the parts 50 are in the latter position, the plunger 8 is in its lowermost position, thereby closing the passage from the part 4 to the soil-pipe 6 and preventing the escape of the water from the tub 3. When however, the member 15 is 55 rotated one-half turn either towards the right or left, the two pins 16 are swung upwardly to the position shown in full lines in Fig. 5. This lifts the plunger 8 away from the seat 4', and effects the draining 60 of the tub 3, by discharging the waste water into the pipe 6. The plunger will then remain in the elevated position, by reason of the spacing of the pins 16, which provide a relatively broad bearing for the loop 14'. 65 To make ready for the next filling of the tub

3, the operator simply grasps the handle 17' and gives it a short twist in either direction, and then lets go. The weight of the plunger 8 will cause it to gravitate towards the seat 4' and effect the reversal of the points 16 and 16' of the member 15, as from the full line to the dotted line position shown in Fig. 5. The shaft 17 and the member 15 carried by it are adjustable relatively to the wall 2 and plate 18, by means of a sleeve 20, which is bored out to operatively receive the said shaft. The inner end of the sleeve 20 is threaded for screwing into a threaded socket 18' in the plate 18 (see Figs. 6 and 7). The outer end of the sleeve 20 is reduced and threaded and is engaged by a cylindrical nut 21, the latter telescoping the free end of the support 19 and having a knurled flange 21', which engages and forces the support tightly against the wall 2. The adjustment of shaft 17 and sleeve 20 is effected by the outer end of the sleeve engaging a split ring 22, which is sprung into a shallow annular groove 17^a of the shaft, the said ring being employed instead of a pin, for obviating the danger of weakening the shaft by boring a hole for the pin. To make the aforesaid adjustment of the shaft 17, the nut 21 and the support 19 are first removed. The sleeve 20 may then be rotated in the proper direction for effecting the endwise shifting of the shaft. After this adjustment is made, a set-screw 23 carried by a lug 18^b of the plate 18 (see Figs. 3 and 4) may be screwed down against the inner end of the sleeve for holding the parts in place. The feet 14^b of the grapple 14 are made of sufficient length to allow a considerable range of adjustment relatively to the cap 9. The provision of the various adjusting means herein shown and described, not only facilitates the assembling of the several parts of the fixture, but enables the erectors to properly install the fittings notwithstanding discrepancies that frequently occur in the roughing-in calculations. The rockable nature of shaft 17 and member 15, ensures the ready and proper operation of the plunger 8 and related parts, whether the said shaft is turned towards the right or left.

Having thus described my invention, what I claim, is—

1. In a waste operating mechanism, the combination with a waste stand-pipe and a gravitational plunger valve, of a manually operable shaft adapted to be rocked in opposite directions for raising and lowering said plunger, a member carried by said shaft and having triangular bearing, and a grapple loosely engaging said bearing and adjustably connected with said plunger. 120
2. The combination with a standing waste fitting including a gravitational plunger, of a manually operable shaft rotatable in opposite directions, a member mounted eccentrically on said shaft, a cap adjustably mount- 125
130

ed on the top-end of said plunger, and a grapple loosely engaging said member and adjustably engaging said cap.

3. In a waste operating mechanism, the combination with a waste stand-pipe and a gravitational plunger valve, of a shaft rockable in opposite directions for raising and lowering said valve, a member rigid on said shaft, a split ring carried by said shaft, means engaging said ring for adjusting said shaft and said member relatively to said plunger, and a lifter operatively connecting said member with said plunger valve.

4. In a waste operating mechanism, the combination with a waste stand-pipe and a plunger carried thereby, of a manually operable shaft adapted to be rocked towards the right or left for raising and lowering said plunger, a member eccentrically mounted on said shaft, a sleeve supporting said shaft and rotatable for adjusting the shaft, and a grapple loosely connected to said member and adjustably connected to the said plunger.

25 5. In a waste valve operating mechanism, the combination with a waste stand-pipe and a gravitational plunger telescoping said pipe, of a rockable shaft disposed horizontally above said pipe, a member rigid on said shaft and having a triangular bearing, the apex of said bearing corresponding to the axis of said shaft, and a lifter loosely riding on said triangular bearing and operatively

connected with said plunger adapted to be raised and lowered by the rotation of said 35 triangular bearing.

6. The combination with a standing waste fitting including a gravitational plunger, of a manually operable shaft, a member mounted eccentrically on said shaft, said member 40 comprising registering discs, the said discs being spaced by a triangular bearing, the apex of said bearing corresponding to the axis of said shaft, and a lifter having a loop which surrounds and rides on said bearing 45 adapted when said bearing is rocked in opposite directions to effect the raising and lowering of said plunger.

7. In a waste operating mechanism, the combination with the plunger valve of a 50 waste fitting, said plunger having a loop, of a shaft adapted to be rocked in opposite directions for actuating said valve, a member eccentrically mounted on said shaft, said member comprising spaced discs, the spacing 55 means providing three bearing points arranged in the form of a triangle, and a lifting device having a loop which surrounds and is adapted to successively engage said bearing points when said member is rocked, 60 and said lifting device having a depending portion which adjustably engages the loop of said plunger.

In testimony whereof I affix my signature.

ORVIS W. VALLIER.
